UNITED STATES PATENT OFFICE.

ADOLPH FREDERICK LIND, OF KITTANNING, PENNSYLVANIA.

COMBINED TABLE AND IRONING BOARD.

Application filed May 14, 1926. Serial No. 109,076.

This invention relates to improvements in a combined table and ironing board and has for its principal object to combine in a single article of furniture a table and an ironing board whereby when the article is in use as a table, the ironing board will be concealed, and when the ironing board is in use, the table will constitute a stand or support for the board and can further be used as a place upon which to deposit the articles after they have been ironed.

A still further object of the invention is the provision of a combined ironing board and table of a construction whereby the table can be of the well known porcelain type.

A still further object of the invention is to provide a device of the character described which is simple in construction, cheap to manufacture, and highly efficient in operation.

Further objects, novel features of construction and improved results of the invention will appear from the following description.

In the accompanying drawings:

25 Figure 1 is a top plan view of the invention, the table top being shown in raised position and the ironing board being shown extended in dotted lines.

30 Figure 2 is a transverse vertical sectional view on the line 2—2 of Figure 1 looking in the direction indicated by arrow.

Figure 3 is an enlarged detail view in side elevation showing the supporting legs of the ironing board.

35 Figure 4 is a vertical sectional view taken at right angles to Figure 2, the ironing board being shown in extended position for use.

Referring now to the drawings in which like parts are designated by similar reference numerals throughout the description, it will be seen that there is provided a table A having the usual four legs 5 on the upper end of which is supported the table top 6 which is hinged at its rear end as at 7. There is provided beneath the table top a compartment formed by the solid table bottom 8 and the table end walls 9, front wall 10 and rear wall 11. This compartment is designated by the letter B.

40 The ironing board proper, designated by the letter C, rests upon the table bottom 8 in an inverted position, as clearly appears in Figures 1 and 2 of the drawings. The bottom of the board adjacent its wide end 12 is provided with downwardly extending por-

tions 13 and 14 placed in separated parallel 55 relation. Fastened to the outer face of the raised portion 13, as at 15 and 16, are the vertical ends 17 of two L shaped brackets 18, the opposite ends of which extend towards the table front and are bent to form eyes 19 which are pivotally supported on the rod 20 which is in turn supported in the upwardly extending ends 21 and 22 of the U shaped bracket 23 which is fastened with the bottom of the U on the table bottom 8 adjacent the front wall of 60 the table. The upper edge of the table front wall 10 is provided with cut-out portions 24 which are positioned in a line with the L shaped brackets 18 and adapted to receive the brackets when the ironing board is swung 65 outwardly into position for use.

A still further object of the invention is the provision of a combined ironing board and table of a construction whereby the table can be of the well known porcelain type.

70 One of the ironing board legs is designated at 25 and when the board is in collapsed position in the table, as shown in Figures 1 and 2 of the drawings, the upper end of this leg assumes a position in the space between the raised portions 13 and 14, being pivotally supported to this raised portion by means of a U shaped crank-like member 26, the ends 27 of which are journaled in the bearings 28. This leg is provided on one edge adjacent its upper end with an eye 29 the purpose of which 75 will be later explained.

The vertical leg of the ironing board is designated at 30 and is provided in its upper end with an elongated slot 31 adapted to receive a pin 32 carried upon the outer face of the raised portion 14 of the ironing board. The extreme upper end of this leg is provided with a notch 33 adapted to engage the pin 34, as clearly appears in Figure 3 of the drawings, when the board is in the extended position. By reason of this construction this leg of the table is very rigid when swung into 80 extended position.

The ironing board is further provided with a brace leg 35, one end of which is pivotally attached as at 36 to the raised portion 37 beneath the narrow end 38 of the ironing board while its opposite end is provided with an elongated slot 39 adapted for sliding engagement with the pin 40 carried by the leg 25. The slot 39 is enlarged at its lower end to provide a seat 41 adapted to receive and hold the pin 40 against sliding movement.

105 A hook and eye 42 is fastened to the under side of the board and this hook is adapted for engagement with the eye 29 carried by

the leg 25, as clearly appears in Figure 3 of the drawings, when the board is swung into extended position.

To render the table more rigid I have provided corner braces 43 which are positioned in the corners of the compartment B.

As an iron is a necessary article for use with this table, I have provided for the purpose of convenience a compartment D in one of the front corners of the main compartment B for the reception of an iron which is shown in dotted lines at 44. This compartment is preferably lined with asbestos.

By reference to Figure 1 it will be seen that I have further provided the table with a small drawer 46 which is made possible by the fact that the ironing board does not utilize the entire table compartment when it is folded in collapsed position for concealment in the compartment.

By reference to Figures 1 and 2 of the drawings it will be seen that when the board is swung into the table compartment that the legs 25, 30 and 35 can be collapsed downwardly upon the lower side or face of the board and thereby use a minimum amount of space in the compartment.

In a device of this nature it is necessary that the board be quite rigid when swung outwardly for use and it will be seen that this has been well taken care of by reason of the notched end at the upper end of the leg 30, the hook 42 which engages the eye 29 of the leg 25 taken together with the brace leg 25 having rigid connection with the ironing board and meeting the leg 25 at a bracing angle.

It is of further advantage in an invention of this nature to be able to lower the table top after the ironing board has been swung outwardly for use. By reason of the brackets 18 sitting in the cut-out portions 24 of the table front wall, the table top can be lowered when the ironing board is in use and will serve as a place upon which to deposit clothes which are being worked upon on the ironing board.

Preferably when preparing the board for use the legs will be swung into operative position while the board is still in the table compartment and after having been positioned the board can then be swung outwardly and the table top lowered. This manner of operating the board is preferable as the legs are more accessible while the board is in the table compartment than after the board has been swung outwardly for use.

It will be seen that when the board has been swung outwardly, it is of a convenient height for persons of the average stature.

Having thus described my invention, what I desire to claim and secure by Letters Patent is:

1. The combination of a table having a hinged top and a compartment below the

same, of an ironing board pivotally supported within said compartment, a leg for said board movably connected thereto and provided with means at its upper end for locking it in vertical position when in use, a second leg movably connected to said board and adapted to be moved into an extended position at an incline in respect to the board when in use, a hook connection between the board and the said inclined leg for holding the leg in its extended position, a brace leg having pivotal connection with the board at one end and a sliding and locking connection with the inclined leg at a point medially of the ends of said inclined leg, a bracket connecting the ironing board with its pivotal support, said bracket of an L shape with one end of the L pivotally connected to the pivotal support and the other end of the L attached to the board, and the leg of the bracket attached to the board being an upstanding vertical leg, whereby the board can be swung outwardly upon the bracket to a position beyond the front of the table and be supported by said bracket and legs in a horizontal plane above the plane of the table top.

2. The combination of a table having a hinged top and a compartment below the same, of an ironing board pivotally mounted wholly within said compartment and provided with a plurality of legs collapsibly supported upon the under side of said board, means to hold said legs in extended positions, an L shaped bracket having its horizontal leg pivotally supported within the compartment and its vertical leg upwardly extending and attached to the ironing board, said board and legs adapted to be swung outwardly on said bracket to a position beyond the front of said table and in a horizontal plane above the table top, and said legs adapted to be moved into extended positions to engage the floor, whereby the table is supported through the medium of said bracket and said legs.

3. The combination of a table having a hinged top and a compartment below the same, of an ironing board pivotally supported within said compartment, a pair of spaced blocks attached adjacent one end of the bottom of said ironing board, a pivotally mounted L-shaped bracket fastened to the outer face of one block, a supporting leg pivotally connected to the outer face of the other block and adapted to be swung into position at right angles to the ironing board, means to lock said leg in said extended position, a second leg movably connected to said blocks by a crank arm and adapted to be swung into an extended position inclined to said ironing board, means to lock said leg in said extended position, a brace leg having pivotal connection at one end with the board and at its other end a pivotal and slideable connection with said inclined leg at a point medially

of its ends, and said board adapted to be swung outwardly upon the L-shaped brackets and be supported by said brackets and legs in front of said table and in a horizontal plane above the table top.

4. The combination with a table having a swinging top and a compartment below the same, of an ironing board pivotally mounted within said compartment and adapted to swing upwardly and outwardly to a position beyond the front of said table, a leg pivotally connected to said board and provided with means at its upper end for locking it in vertical position when in use, a second leg mov-
ably connected to said board and adapted to

be moved to an extended position at an incline to said board when in use, means at the upper end of said second leg for locking it in said inclined extended position, a brace leg having pivotal connection with the board 20 at one end and a sliding and locking connection with the second leg at a point medially of its ends, and said brace leg and said second leg arranged approximately at right angles to one another when in their extended positions.

In testimony whereof I hereunto affix my signature.

ADOLPH FREDERICK LIND.
